HYDRAULIC PUMP OR MOTOR

Warren R. Tucker, Dayton, Ohio, assignor to
The Hydraulic Development Corp. Inc., Wil-
mington, Del., a corporation of Delaware

Application May 20, 1940, Serial No. 336,122

8 Claims. (CL 103—161)

This invention relates to hydraulic pumps or motors, and in particular to a hydraulic pump having a plurality of reciprocating pistons in which one or more pistons perform a suction stroke, while simultaneously, one or more pistons perform a pressure stroke.

One object of this invention is to provide a hydraulic pump or motor of the above identified type, in which a pressure stroke performing piston is hydraulically connected with a suction stroke performing piston so as to aid the latter in carrying out its suction stroke.

Another object of the invention is to provide a hydraulic pump with a plurality of asynchronously operating pistons in which at least one of the pistons carries out a pressure stroke, while another piston performs a suction stroke, and in which a portion of the fluid pressure created by a pressure stroke performing piston is conveyed to a suction stroke performing piston for aiding the movement thereof.

Another object is to provide a hydraulic pump or motor having radial pistons reciprocable in a radially bored primary rotor in which at least one pressure stroke performing piston supplies pressure fluid to at least one suction stroke performing piston, to continuously urge the latter upwardly.

Still another object of the invention consists in providing a hydraulic pump or motor of the radial piston type, in which the radial pistons reciprocate in a radially bored primary rotor, and engage with their outer ends, recesses in a secondary rotor, and in which the suction stroke performing pistons are continuously held in engagement with said secondary rotor by pressure fluid created by a pressure stroke performing piston.

A still further object of the invention consists in providing a hydraulic pump, as set forth in the preceding paragraphs, which is simple in construction, cheap in manufacture, and reliable in operation.

These and other objects and advantages will appear more clearly from the following specification in connection with the accompanying drawings, in which:

Figure 1 is a longitudinal vertical section through a pump assembly according to the invention.

Figure 2 illustrates a transverse section along the line 2—2 of Figure 1.

Figure 3 shows, on a somewhat larger scale, a section along the line 3—3 of Figure 1, and

Figure 4 illustrates, likewise on a larger scale, a detail of the invention.

Referring to the drawings in detail, the pump shown in the drawings and generally designated 10 is of the variable radial piston type, and comprises the casing halves 11 and 12, these being held together in any convenient manner, for instance, by the machine screws 13. The casing half 12 is provided with a projecting portion 14 having a bore 15 which serves for supporting the pintle 16. The projecting portion 14 is provided with a threaded passage 17 serving as one port, for instance, outlet port and connected to the pipe 18.

A similar threaded passage 19 connects the opposite side of the projecting portion 14 with the pipe 20. The passages 17 and 19 lead inwardly so as to communicate with the ducts 21 and 22 respectively, leading to the passages 23 and 24 of the pintle 16. The passages 23 and 24 lead to the transverse ducts 25 and 26 opening into the cut-away portion 27 and 28 near the mid-portion of the pintle. By this means fluid is conducted to and from the cylinders of the pump, as herein-after explained.

Immediately adjacent the cut-away portions 27 and 28, the pintle 16 is provided with an enlarged portion 29. Immediately beyond the latter is a portion 30 which is substantially of the same diameter as the pintle portion 31, supported in the end projecting portion 14 of the casing half 12. The pintle terminates on its righthand end in a threaded portion 32. Surrounding the pintle portions 31 and 32 are the inner races 33 and 34 of tapered roller bearings 35 and 36. The outer races 37 and 38 are mounted in depressions 39 and 40 in the opposite ends of a cylinder barrel or primary rotor 41. The latter, at its central portion, closely surrounds the enlarged pintle portion 29, and is provided with radial cylinder bores 42 communicating with the cut-away portions 27 and 28 of the pintle 16 and having pistons 43 reciprocable therein.

The pistons, as shown in the drawings, are provided with rounded outer ends 44 adapted to engage the guide ring 45 and to move relative thereto. However, if desired, the rounded ends 44 may be shaped in any other desired manner to reduce the friction between the piston ends 44 and the guide ring 45 to a minimum. To this end, for instance, balls supported by the pistons 43 may take the place of the rounded ends 44.

It may also be mentioned that, instead of the guide ring 45, spaced guide ring segments may be provided each having a recess to be engaged by the adjacent piston end. However, since in the construction shown in the drawings, the relative

movement between the piston ends 44 and the guide ring 45 is very small, the provision of a guide ring 45 and rounded piston heads 44, as shown in the drawings, has proved highly satisfactory.

The cylinder barrel 41 is provided with a series of segmental ridges 49 extending between the cylinder bores 42 and adapted to provide additional support for the pistons 43 during their reciprocation.

The peripheral surface 48 of the guide ring 45 engages anti-friction bearing elements such as the rollers 50. These, in turn, engage the inner surface 51 of the shift ring 52, which latter surface has an outer bearing race. The rollers 50 are maintained in position by retaining rings 53 resting in the recesses 54 in the shift ring 52, and having annular grooves 55 engaging the corresponding projections 56 on the ends of the rollers 50. At the top and bottom thereof, the shift ring 52 is provided with flattened portions 57 and 58 of the casing half 12. At the opposite ends of its horizontal diameter the shift ring 52 is provided with flattened portions 59 and 60. The flattened portion 59 is engaged by a coil spring 61 mounted in a boss 62 having a threaded bore 63 closed by a threaded adjusting plug 64.

By varying the position of the plug 64 in the threaded bore 63, the tension of the spring may be varied. The flattened portion 60, however, is engaged by one end of a pilot piston 65 reciprocable in a cylinder bore 66 in a boss 67 of the casing half 12. The cylinder bore 66 is provided with a threaded outlet port 68 in which is secured the end of the pilot line 69 connected with the pressure outlet side of the pump. In this way, a predetermined pressure in the pressure outlet side of the pump will cause the pilot piston 65 to move toward the left (with regard to Figure 2), thereby shifting the shift ring 52 toward neutral position.

The threaded portion 32 at the inner end of the pintle 16 is provided with a nut 10 and a lock washer 11 adapted to engage the inner race 33 of the tapered roller bearing 35. A key way 12 is also provided in the threaded end portion 32 and extends into the pintle portion 30. A key within the key way 12 forms part of the lock washer 11 and prevents it from rotating, and at the same time, an ear extending from the lock washer 11 engages one of the slots in the edge of the nut 10 and prevents the rotation of the latter.

The opposite outer end of the pintle 16 is similarly provided with a threaded portion 73 having a key way 74 therein. A key within the key way 74 likewise forms a part of the lock washer 75 and prevents the lock washer from turning, whereas an ear on the lock washer engages one of the slots in the edge of the nut 16 upon the threaded portion 73 and prevents the rotation of the nut. By turning the nut 16 with the lock washer 75 released, the pintle 16 may be made to move longitudinally to adjust the clearances of the tapered roller bearings 35 and 36.

When, for example, the pintle 16 is moved to the left, the nut 10 and its lock washer 11 push the inner race 33 against the rollers 35, and the latter push the outer race 37 and the cylinder barrel 41 to the left. This action closes the clearances existing between the rollers 36 and the inner and outer bearing recesses 34, 38, the inner bearing recess being kept from moving by its engagement with the inner wall of the

casing half 12. After this adjustment is made, the lock washer 11 may be bent to lock the nut 16 in the position of adjustment. The casing half 11 of the pump 10 is provided with a recess 77 in which is mounted the outer race 78 of a ball bearing 79, the inner race 80 of which is mounted upon the enlargement 81 of the drive shaft 82. The drive shaft 82 is provided with a further enlarged portion 83 which is secured 10 to the cylinder barrel 41 by means of the screws 84 (Figure 1).

The cylinder barrel 41 has provided therein a plurality of radial bores 85 closed at their outer ends by a washer 86 pressed against a shoulder 87 by threaded plugs 88. The lower ends of the radial bores 85 communicate with an annular groove 89 which in turn communicates with bores 90 and 91, respectively provided in nuts 92 and 93 which are threaded into the pintle portion 29. The pintle portion has in alignment with the bores 90 and 91 of the nuts 92 and 93, the bores 94 and 95 of somewhat larger diameter which respectively house a ball 96 and 97 pressed against valve seats 98 and 99 by means of a spring 100 and 101, thereby preventing communication between the bore 94 and the passage 23 and between the bore 95 and passage 24.

The thrust of the spring 100 and 101 is such as to allow the balls 96 and 97 respectively to re-cede from their respective valve seat when a predetermined pressure is established in the passages 23 and 24. The radial bores 85 communicate with transverse bores 102, one end of which is closed by a plug 103 while the other end communicates with an annular recess 104 in the pistons 43. Communicating with the recess 104 in each piston 43 is a transverse bore 105 leading to an axial bore 106 in the respective piston 43. The bore 106 forming a booster cylinder, is engaged by a plunger 107 rigidly connected with the barrel 41 by means of the arm 108, so that pressure liquid introduced into the booster cylinder 106 causes the respective piston 43 to engage the guide ring 45.

Operation

In the operation of the pump assembly, shown in the drawings, power is applied to the drive shaft 82 from any convenient source, such as an electric motor. The rotation of the drive shaft 82 causes the rotation of the barrel or primary rotor 41. When the shift ring 52 is moved laterally, for instance, toward the right, as shown in Figure 2, so that its axis is eccentric to that of the pintle 16, the pistons 43 are reciprocated in the cylinder bores 42 when the cylinder barrel or primary rotor 41 rotates. As the pistons 43 reciprocate, their rounded ends 44 engage the guide ring 45 and move in an annular path while approaching the center of the pump during one-half of the revolution, and receding during the other half. During this rotative movement of the pistons, only a slight movement thereof relative to the guide ring 45 is effected in correspondence to the eccentricity between the guide ring 45 and the primary rotor 41.

While during rotation of the cylinder barrel or primary rotor 41, the centrifugal force tends to move the pistons 43 toward the outside, it might, without any additional means, occur that the suction effect on the lower end of the pistons 43 prevents the latter from duly engaging the guide ring 45.

However, according to the present invention, such undue operation is prevented due to the

fact that fluid pressure from those pistons 43 performing a pressure stroke is conveyed into the booster cylinders 106 of those pistons 43 performing a suction stroke, so that the pressure fluid in the said booster cylinders causes the suction stroke performing pistons to engage with the adjacent surface of the guide ring 45. Supposing, for instance, that the pressure stroke performing pistons deliver pressure fluid into the passageway 24, then pressure in the passageway 10 lifts the ball 87 from its valve seat 89 so that pressure fluid passes from the passageway 24 into the bore 85, and from there through the bore 81 into the annular groove 89. From here, pressure fluid passes through the radial bores 85 and the transverse bores 102 into the annular recess 104 of those pistons which perform a suction stroke, and hence into the respective booster cylinders 106. In this way, all pistons 43 are constantly maintained in engagement with the guide ring 45.

The reciprocation of the pistons 43, in this manner, causes pressure fluid to be discharged from the outlet pipe 20 and thus fluid passes onward to the machinery or circuit which is intended to be operated, while fluid from a fluid source, such as a fluid tank, enters the pump through the inlet pipe 18 and the passageway 23. From here it passes to the suction stroke performing pistons. If the fluid pressure exceeds a predetermined value, the fluid reaching the pilot cylinder bore 86 through the branch line 89 acts upon the pilot piston 85 urging it to the left (with regard to Figure 2) and with it the shift ring 52, thereby overcoming the thrust of the coil spring 81. This action tends to move the shift ring toward its neutral position so as to reduce the discharge of the pump.

It will be understood that I desire to comprehend within my invention such modifications as my come within the claims and scope of the invention.

Having thus fully described my invention, what I claim as new and desire to secure by Letters Patent is:

1. A fluid pump or motor comprising an inlet conduit, an outlet conduit, a plurality of cylinder bores, pistons reciprocably mounted in said cylinder bores and adapted alternately to take in fluid through said inlet conduit and to press fluid into said outlet conduit, booster cylinders provided in said pistons and cooperating with correspondingly shaped booster plungers, and means adapted automatically to connect said outlet conduit with the booster cylinder of a suction stroke performing piston to aid the latter in its suction stroke.

2. A fluid pump or motor comprising an inlet conduit, an outlet conduit, a plurality of main cylinders each having reciprocably mounted therein a main piston adapted alternately to take in fluid from said inlet conduit and to press fluid into said outlet conduit, an auxiliary cylinder provided in each piston and cooperating with an auxiliary piston stationary with regard to the respective main cylinder, and means responsive to the supply of pressure fluid to said outlet conduit by a pressure stroke performing main piston to connect said outlet conduit with the auxiliary cylinder of each piston performing a suction stroke to aid the same in its suction stroke.

3. A fluid pump or motor comprising an inlet conduit, an outlet conduit, a plurality of main cylinders, pistons reciprocably mounted in said main cylinders and adapted alternately to take in

fluid from said inlet conduit and to press fluid into said outlet conduit, each piston being provided with an auxiliary cylinder having telescoped therein a plunger maintaining stationary with respect to the main cylinders, and valve means responsive to the creation of fluid pressure by a pressure stroke performing piston to connect said outlet conduit with the auxiliary cylinder of each suction stroke performing piston to aid the same in its suction stroke.

4. A fluid pressure pump or motor comprising a rotor with radial cylinder bores, pistons reciprocable in said bores and adapted alternately to perform a suction stroke and a pressure stroke, a control member surrounding said rotor and shiftable into eccentricity with respect to said rotor, said control member including a guiding means for said pistons, each piston having formed therein an auxiliary cylinder with a plunger telescoped in said auxiliary cylinders, conduit means adapted to connect the pressure side of each pressure stroke performing piston with the auxiliary cylinder of each suction stroke performing piston, and valve means responsive to a pressure stroke of said pistons for effecting communication between an auxiliary cylinder and the pressure side of a pressure stroke performing piston to cause each suction stroke performing piston to remain in contact with said guiding means.

5. A fluid pressure pump or motor comprising a cylinder barrel having cylinder bores, pistons reciprocably mounted therein and adapted alternately to perform a suction stroke and a pressure stroke, each piston being provided with an auxiliary cylinder, guiding means surrounding said cylinder barrel and adapted to be shifted into eccentricity with respect to said cylinder barrel, said guiding means being engageable by said pistons, a stationary but adjustable pintle mounted within said cylinder barrel and rotatably carrying said cylinder barrel, a plurality of plungers carried by said cylinder barrel, one plunger being associated with the auxiliary cylinder of each piston, and conduit means provided in said cylinder barrel and adapted to effect communication between the pressure side of each pressure stroke performing piston and the auxiliary cylinder of each suction stroke performing piston.

6. A fluid pressure pump or motor comprising a casing, a pintle therein, a cylinder barrel rotatable on said pintle, main pistons reciprocable radially in said cylinder barrel and adapted alternately to perform a pressure stroke and a suction stroke, each main piston having an outwardly disposed head and forming one part of an auxiliary cylinder piston assembly, the other cooperating part of which is carried by said cylinder barrel, guiding means shiftable selectively into or out of concentricity with said barrel and directly engaging said piston heads, and means adapted in response to a pressure stroke of said main pistons to supply pressure fluid from the pressure side of each pressure stroke performing main piston to the auxiliary cylinder piston assembly of each suction stroke performing main piston to maintain the latter in engagement with the adjacent surface of said guiding means.

7. A fluid pressure pump or motor comprising, a pintle, a cylinder barrel rotatably supported on said pintle, pistons reciprocable radially in said barrel and adapted alternately to perform a suction stroke and a pressure stroke, each piston having an auxiliary cylinder with a plunger

telescoped therein, and stationary with respect to said cylinder barrel, inlet conduit means adapted to communicate with the suction side of each piston, outlet conduit means adapted to communicate with the pressure side of each piston, and valve means responsive to the pressure stroke of said pistons for establishing hydraulic communication between said outlet conduit means and the auxiliary cylinder of each suction stroke performing piston to admit pressure fluid to the latter for aiding the same in its suction stroke.

8. In a fluid pressure pump or motor having a rotor with a plurality of radially arranged main cylinders and a ring member surrounding said rotor and movable selectively from a position concentric to said rotor to a position eccentric thereto or vice versa, a plurality of main pistons respectively reciprocable in said main cylinders

5 and adapted alternately to perform a suction stroke and a pressure stroke while being guided by said ring member, each of said main pistons comprising one part of an auxiliary cylinder piston assembly, the cooperating other part of which is carried by said rotor and stationary with respect thereto, conduit means respectively associated with said auxiliary cylinder piston assemblies for admitting pressure fluid into and releasing pressure fluid from said auxiliary cylinder piston assemblies, and means for establishing communication between a main cylinder of a pressure stroke performing main piston and an auxiliary cylinder piston assembly pertaining to a suction stroke performing main piston to maintain the latter in engagement with said ring member.
